US00D452241B1

(12) **United States Design Patent**
Kitajima et al.

(10) Patent No.: **US D452,241 S**
(45) Date of Patent: **** Dec. 18, 2001**

(54) **IMAGE COMPRESSION TRANSMISSION
CONTROL EQUIPMENT**

(75) Inventors: **Yasuhiro Kitajima; Sadaaki
Miyamoto; Ou Matsumoto; Tsuneo
Shimada**, all of Tokyo (JP)

(73) Assignee: **NEC Corporation**, Tokyo (JP)

(**) Term: **14 Years**

(21) Appl. No.: **29/133,452**

(22) Filed: **Dec. 1, 2000**

(30) **Foreign Application Priority Data**

Aug. 8, 2000 (JP) 2000-021847

(51) LOC (7) Cl. **14-02**

(52) U.S. Cl. **D14/358**

Macpeak & Seas, PLLC

(57) **CLAIM**

The ornamental design for image compression transmission control equipment, as shown.

DESCRIPTION

FIG. 1 is a perspective view of the top, front and right side of image compression transmission control equipment showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
